United States Patent Office

Des. 229,116
Patented Nov. 6, 1973

229,116

CASE FOR MANICURING IMPLEMENTS OR THE LIKE

Shogo Ishii, Tokyo, Japan, assignor to
Syntak Company, Ltd.

Filed Nov. 1, 1971, Ser. No. 194,781

Term of patent 14 years

Int. Cl. D3—99

U.S. Cl. D86—10 C

Fig. 1

Fig. 2

Fig. 3

Fig. 4

FIG. 1 is a top plan view of a case for manicuring implements or the like embodying my new design;

FIG. 2 is a front elevational view;

FIG. 3 is a bottom plan view; and

FIG. 4 is a side elevational view thereof.

I claim:

The ornamental design for a case for manicuring implements or the like, as shown.
